Patented July 4, 1916.

UNITED STATES PATENT OFFICE.

NILS OLAF HEDMAN, OF LEADVILLE, COLORADO.

JACK.

1,190,163.

Specification of Letters Patent.

Patented July 4, 1916.

Application filed August 2, 1915. Serial No. 43,321.

To all whom it may concern:

Be it known that I, NILS O. HEDMAN, a citizen of the United States, residing at Leadville, in the county of Lake and State 5 of Colorado, have invented certain new and useful Improvements in Jacks, of which the following is a specification.

The object of the present invention, which relates to improvements in jacks, is to provide 10 means for lifting an object in a vertical direction and independent means for moving the lifted object in a horizontal plane. Such implements are particularly designed for use in moving large and heavy 15 objects such as houses, cars and the like, and the essential characteristics of the present device reside primarily in the provision of a screw having an operating member for raising the same, actuating mechanism carried 20 by said screw, and means on which the object to be moved rests, said last-mentioned means being positively actuated by the aforesaid actuating mechanism.

More specifically, the jack comprises a 25 swiveled head carried by the screw, a gear element mounted therein, an operating member for said gear, a rack member engaging the gear for movement thereon, and means for locking the head from swiveling action 30 during movement of the object borne by the rack.

With the above and other objects in view, this invention consists in the construction, 35 combination and arrangement of parts all as hereinafter more fully described, claimed and illustrated in the accompanying drawing, wherein:—

Figure 1 is a side elevation, partly broken away and in section, of a preferred embodiment of my device. Fig. 2 is a horizontal sectional view taken about on the plane indicated by the line 2—2 of Fig. 1. Fig. 3 is a similar section taken on the line 3—3 of Fig. 1. Fig. 4 is a fragmentary sectional view approximately on the line 4—4 of Fig. 2. Fig. 5 is a sectional view on the line 5—5 of Fig. 1; and Fig. 6 is a perspective view of a slightly different form of rack for use 45 in conjunction with this device.

Throughout the following detail description, and on the several figures of the drawing, similar parts are referred to by similar reference characters.

Referring to the drawing, the numeral 1 50 refers to a base in which is mounted a lifting screw 2, said screw having a squared ex-

tremity as indicated at 3, carrying a detachable sleeve 4 coacting with an opening 5 in the base 10 square in cross section.

Upon the upper end of the base 1 is rotatably mounted an exteriorly toothed collar 6, said collar resting upon suitable bearings 7 for facilitating rotation in the use of this device. Surrounding the collar is a lifting lever 8, said lever comprising a movable section 8' pivoted at 9, a reversible dog 10 and a knurled locking nut 11 coacting with the free end of the section 8' and the handle of the lever for holding said lever in position about the collar 6. The dog 10 is held in its position by means of a spring actuated cam 12, and said dog controls the raising and lowering of the screw 2 upon actuation of the lever 8 according to which extremity of the dog is coacting with the toothed collar 6.

The screw at its upper end is provided with an annular flange 13 constituting a seat for the jack head 14 which preferably rests upon bearings 15 interposed between the head and the flange above referred to. The head is, therefore, capable of swiveling action and this is particularly advantageous in constructions of this character. The head 14 is hollow in formation and disposed within said head is a traversing gear 16 mounted upon the axis 17 having its bearing in the head. The gear 16 at one side is provided with a rectangular shaped recess in cross section to receive the lateral projection 18 of a pinion 19 interlocking said parts together, the pinion, as most clearly shown in Fig. 2, being carried by the outer extremity of the axis or bolt 17 just referred to. Surrounding the pinion 19 and adapted for actuation thereof is a lever 20 similar in construction to the lever 8, being provided with a reversible dog 21 whereby said pinion and consequently the traversing gear 16 may be rotated in either direction.

The gear 16 is adapted to be locked from rotation in either of its directions of movement by means of oppositely disposed spring actuated pawls or locking members 22 similar in construction and coaction and normally tending to engage the gear 16. These locking members are provided with exteriorly arranged manipulating means 23 for engaging and disengaging the respective pawls with the gear 16, the members 23 being furthermore, provided with locking pins 24 for engaging with the face of the head to

hold the pawls in unlocked or disengaged position with respect to the gear 16.

The head 14 is provided with suitable locking means for preventing swiveling action thereof during use of the invention, as hereinafter more fully set forth, and such means in the drawing, is in the form of a hook 25 carried by the casing and adapted to engage in a recess 26 in the flanged extremity of the screw 2. This flange may be provided with any suitable number of recesses for this purpose, so that the head may be locked at any desired position.

As will be noted by reference to Fig. 1, the gear 16 projects slightly above the head of the jack and I preferably employ a rack member 27 for engaging the object to be lifted, said rack resting upon the gear 16. It will be obvious that when an object has been lifted by operation of the lifting lever 8, said object may have imparted thereto traversing movement by actuation of the lever 20. By reason of the swiveling of the head, the object may be moved in any desired direction according to the disposition of the rack member 27 upon which said object is adapted to rest. In order to prevent movement in an undesired direction, by reason of the swivel connection of the head to the screw, said head may be locked by means of the hook member 25 so as to insure the movement of the object in the manner desired. When it is desired to give an arcuate movement to the object lifted, it is contemplated to use instead of the type of rack disclosed in Fig. 1, an arcuate shaped rack 27', such as disclosed in Fig. 6 of the drawing. These racks may be suitably cut away at their extremities to permit of overlapping of sections and formation of a continuous rack member such as desired when the object to be lifted is to be moved a considerable distance. With a device of this character, cars, or houses may readily be displaced or properly positioned quickly by reason of the adjustability of the parts of the jack. It is to be understood that the rack member hereinbefore mentioned may be dispensed with under certain conditions and the gear element 16 allowed to coact with the object to be lifted under which condition the traversing movement may be quickly accomplished but it is preferred to employ the rack member, both for the purpose of preventing mutilation of said object as well as facilitating the movement imparted thereto.

Having thus described my invention, what I claim as new is:

1. In a jack of the class described, the combination of a base, a lifting member mounted thereon, a head swiveled on said lifting member, actuating means projecting from said head, operating means for said actuating means, and a member adapted for engagement with the object to be moved and

geared to the actuating means for imparting traversing movement to the object mentioned.

2. In a jack of the class described, the combination of a base, a lifting member mounted therein, a head swiveled on said lifting member, actuating means carried by said head for imparting traversing movement to the object lifted, and means for locking the head from swivel action at any of a number of different positions.

3. In a jack of the class described, the combination of a base, a lifting member mounted therein, a head swiveled on said lifting member, actuating means comprising a gear projecting from the head and an operating member therefor, a toothed rack for carrying the object lifted and with which said gear member meshes, and locking means for holding the head from swiveling during actuation of the gear.

4. In a jack of the class described, the combination of a base, a lifting member mounted therein, a head swiveled on said lifting member, actuating means carried by said head for imparting traversing movement to the object lifted, and means for locking the head from swivel action, comprising a hook pivotally connected to the head and adapted for engagement with the lifting member, said member having a recess in which said hook interlocks.

5. In a jack of the class described, the combination of a base, a lifting member mounted therein, a hollow head carried by said lifting member, a gear member therein, locking members for holding said gear from movement in either direction, a pinion disposed exteriorly of the head and having fixed relation with the gear aforesaid, and an operating lever coöperating with the pinion for operating said gear.

6. In a jack of the class described, the combination of a base, a lifting member mounted therein, a hollow head carried by said lifting member, a gear member therein, locking members for holding said gear from movement in either direction, a pinion disposed exteriorly of the head and having fixed relation with the gear aforesaid, an operating lever coöperating with the pinion for operating said gear, and manually operable means connected to the locking members for holding the same in or out of relation to the gear member.

7. In a jack of the class described, the combination of a base, a lifting screw mounted therein, operating means for said screw, a head carried by said screw, a traversing gear mounted in said head, an axle therefor, said gear having a recess at one side, a pinion disposed exteriorly of the head on the axle and having a projection interlocking in the recess of said gear, an operating member for said pinion comprising

ing a lever having an arcuate terminal and a pivoted section connected thereto for surrounding the pinion aforesaid, and a reversible dog engaging said pinion whereby to 5 actuate the pinion and the gear in either direction.

8. In a jack of the class described, the combination of a base, a lifting screw mounted therein, a gear member coöperating with 10 said lifting member, and an operating lever for said gear member comprising a lever

having an arcuate shaped terminal, a similarly shaped section pivoted to the terminal whereby to surround the gear, a reversible dog mounted in said handle for engagement with the gear, spring actuated means for controlling said dog, and a locking member on said lever for holding the pivoted section in position.

In testimony whereof I affix my signature. 20

NILS OLAF HEDMAN.
